UNITED STATES PATENT OFFICE.

HARRY A. DOUGLAS, OF BRONSON, MICHIGAN.

ELECTRIC SWITCH.

Application filed April 11, 1923. Serial No. 631,290.

To all whom it may concern:

Be it known that I, HARRY A. DOUGLAS, citizen of the United States, residing at Bronson, in the county of Branch and State of Michigan, have invented a certain new and useful Improvement in Electric Switches, of which the following is a full, clear, concise, and exact description.

My invention relates to lock switches for controlling electric circuits and has for its general object the provision of improved means for assembling the movable member of the lock of such a switch with the balance thereof.

15 In accordance with my invention the movable member of the lock is held in place by spring pressure. In the preferred embodiment of the invention the contact actuator which is governed by the movable member of the lock is fast with respect to such movable member to constitute therewith a unitary structure, these two parts being preferably formed in one integral piece. The movable lock member together 20 with the contact actuator in the same unitary structure therewith desirably float, being positioned by spring means, preferably a spring pressed contact or contacts of the switch.

30 A switch thus constructed is of particular utility when embodied in mechanism that also employs a handle adapted to govern another set of contacts and in the axial portion of which the lock mechanism is disposed. The switch structure of my invention is much simplified as compared with prior switches and less liable to get out of repair.

35 The invention will be explained more fully by reference to the accompanying drawing in which Fig. 1 is a sectional view taken on line 1-1 of Fig. 2 which is a sectional view on line 2-2 of Fig. 5; Fig. 3 is a sectional view on line 3-3 of Fig. 5 illustrating the manner in which a mounting nut is assembled with the casing and its mounting plate; Fig. 4 is a sectional view with a portion of the handle shown in elevation and with some of the parts removed. 40 Fig. 5 is a sectional view on line 5-5 of Fig. 2; Fig. 6 is a sectional view illustrating complementary contacts upon two contact carriers; and Fig. 7 is a perspective view of a portion of the handle looking from the inside thereof.

55 Like parts are indicated by similar charac-

ters of reference throughout the different figures.

The casing has an end wall 1 and a side wall 2, the wall 1 being essentially flat and the wall 2 being preferably cylindrical. The mounting plate 3 is disposed at the end wall and upon the exterior of the casing beyond which the mounting plate laterally projects. One of these elements, preferably the mounting plate, is formed with a plurality of tongues 4 which project through openings formed in the end wall 1 of the casing. These tongues are laterally deflected as indicated at 5 so that the end wall is interposed and clamped between the laterally deflected ends of the tongues and the body portions of the mounting plate. The mounting plate is desirably circular and coaxial with the casing and it has a central circular raised portion 6 which is concentric with the mounting plate and the casing and through which a large circular opening 7 is formed, this opening being likewise coaxial with the casing and plate. One or more arcuate slots 8, also concentric with the casing, are formed through the end wall thereof and are aligned with the opening 7, these slots being formed in depressed portions 9. The end wall of the casing and the raised portion 6 of this mounting plate are spaced apart to receive arcuate flanges 10 formed upon one end 11 of the handle, these flanges, the end wall of the casing, and the casing mounting plate co-operating to define a plane of rotation or oscillation for the handle. The switching mechanism includes an actuating member 12, here shown as being in the form of a ring. This ring is formed with wide notches 13 upon its inner circular face. These notches receive the handle portions 14 which project into the interior of the casing through the arcuate slots 8. Said notches or openings are of such shape as to prevent material relative turning movement of the handle and actuating member while desirably permitting sliding movement of the actuating member upon the handle.

50 A contact carrier 15 carries bayonet pins 16 that are receivable in bayonet slots 17 formed in the cylindrical wall of the casing. This contact carrier carries contacts 18, 19, 20, etc. which pertain to the different circuits, the circuit relation thereof being immaterial so far as my invention is concerned. These contacts are shown in the form of

threaded rods which are screwed into holes that are formed through the contact carrier and are provided with suitable binding screws upon the outer ends as indicated at 5 21. The inner ends of the rods 18 are slightly dished so as to receive contacts that are provided upon one or more contact carriers that are supplied in addition to the contact carrier 15. Another contact carrier 10 22 is interposed between the contact carrier 15 and the contact actuator 12, the contact carrier 22 being desirably in the form of a metallic ring which is co-axial with the actuating member 12 and the switch casing. 15 The ring 22 carries a series of metallic contacts 23 which are formed with spring barrels 24 that have clinching formations 25 upon one side of the ring to hold this ring in firm assembly with the contacts 23 upon 20 the other side of this ring. The spring barrels 24 slide within openings formed transversely through the actuating ring 12 whereby this actuating ring engages sides of these barrels to force the barrels to turn therewith 25 whereby the ring 12, in being turned, will turn the ring 22 to shift the contacts 23 into and out of engagement with the complementary contacts upon the carrier 15. This carrier is formed with depressions, 30 clearly illustrated in Fig. 2, which receive the contacts 23 when the switch is in open circuit position, the carrier 15 being formed of insulating material.

The contacts 23 are pressed toward the 35 carrier 15 and the actuating ring 12 is pressed against the depressed portions 9 of the end wall of the casing by means of coiled springs 26 that are located within the spring barrels 25, these coiled springs pressing each 40 at one end upon the contacts 23 and each at its other end against the actuating ring 12. The springs 26 desirably exert their pressure upon the latter ring through the intermediation of plungers or buttons 27 45 that extend into the barrels and project therefrom for the purpose. By the assembly illustrated the contact actuating ring 12 may perform its function without binding the springs 26.

50 There is a central sleeve 28 that is co-axial with the handle and with the casing and other rotating parts of the switch. This sleeve 28 houses the barrel 29 of any suitable lock which is accessible from the front of 55 the handle. The sleeve is shown with slots 30 into which the tumblers 31 of the lock may be projected when operated by a key in order to lock the inner contact carrier 34 and from which the tumblers may be 60 withdrawn when the contact carrier 34 is to be unlocked and readjusted, the handle controlled switch being preferably always adjustable.

The contact carrier 34 is interposed be- 65 tween the contact carriers 12 and 15 and

between the lock member 29 and the contact carrier 15. The oscillatable part 29 of the lock is made in a unitary structure with the contact actuator 35, being preferably formed in one integral piece therewith. The unitary structure 29-35 desirably floats. The outer end of the barrel 29 is in thrusting engagement with the outer inturned end of the sleeve 28, this engagement being effected by the contact springs 26' of spring pressing structures upon the carrier 34, these spring pressing structures being similar to the spring pressing portions of the contact structures upon the carrier 12, parts of the spring pressing structures upon the contact carrier 34 that are similar to parts of the spring pressing structures upon the contact carrier 12 being given similar characters of reference with prime exponents added. The actuator 35 is brought into actuating relation with the contact carrier 34 by receiving parts 24', 27' which are pressed upon in opposite directions by the springs 26', parts 24' being assembled with the carrier 34. One of these parts 24' is shown as being 90 provided with a contacting portion 23' that may be brought into and out of engagement with the complementary contact upon the carrier 15. The contact carrier 34 is thus also 95 interposed between the contact carrier 15 and the contact actuator 35. The contact carrier 34 is shown as being in the form of a metallic plate and has a central depression 36, co-axial with the lock member 29, which depression 36 is received upon the inner end of the central contact 19, these portions 36 and 19 constituting complementary contacts as the switch is illustrated. The contact carrying plate 34 is thus obviously mounted to be turned to the extent defined by the turning movement of the combined oscillating lock member 29 and contact actuator 35. The range of movement of these combined parts 29 and 35 is limited by an inner lug 37 upon the end wall of the casing and the 100 end walls of the arcuate slot 38, receiving the lug 37, formed in the flat face of the actuator 35 that is adjacent the end wall of the casing.

While the lock tumbler and one of the 115 contact actuators are preferably parts of the same unitary structure, the invention is not to be thus limited, as I believe it to be new with me to assemble the lock member alone in the manner described.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. A lock switch including a contact car- 130

- rier; a contact actuator; complemental contacts coupled with said carrier and actuator; a lock having a floating movable member included in a unitary structure with said contact actuator, and a shell enclosing the movable lock member; and a spring between said contact carrier and the movable lock member that positions the movable lock member in its shell.
- 10 2. A lock switch including a contact carrier; a contact actuator; complemental contacts, inclusive of a spring pressed contact, coupled with said carrier and actuator at the adjacent faces thereof; and a lock having a floating movable member included in a unitary structure with said contact actuator, and a shell enclosing the movable lock member, the spring pressed contact serving to position the movable lock member in its shell.
- 15 3. A lock switch including a contact carrier; a contact actuator; a lock having a floating oscillatable member included in a unitary structure with said contact actuator, and a shell enclosing the oscillatable lock member; and a spring between said contact carrier and the oscillatable lock member that positions the oscillatable lock member in its shell.
- 20 4. A lock switch including a contact carrier; a contact actuator; complemental contacts, inclusive of a spring pressed contact, coupled with said carrier and actuator at the adjacent faces thereof; and a lock having a floating oscillatable member included in a unitary structure with said contact actuator, and a shell enclosing the oscillatable lock member, the spring pressed contact serving to position the oscillatable lock member in its shell.
- 25 5. A lock switch including a contact carrier; a contact actuator; complemental contacts, inclusive of a spring pressed contact, coupled with said carrier and actuator; and a lock having a movable member in actuating relation with said contact actuator and held in place by the spring pressed contact.
- 30 6. A lock switch including a contact carrier; a contact actuator; complemental contacts coupled with said carrier and actuator at the adjacent faces thereof; and a lock having a floating movable member in actuating relation with said contact actuator, and a shell enclosing the movable lock member; and a spring between said contact carrier and the movable lock member that positions the movable lock member in its shell.
- 35 7. A lock switch including a contact carrier; a contact actuator; complemental contacts, inclusive of a spring pressed contact, coupled with said carrier and actuator at the adjacent faces thereof; and a lock having a floating movable member in actuating relation with said contact actuator, and a shell enclosing the movable lock member, the spring pressed contact serving to position the movable lock member in its shell.
- 40 8. A lock switch including a contact carrier; a contact actuator; complemental contacts, inclusive of a spring pressed contact, coupled with said carrier and actuator; and a lock having an oscillatable member in actuating relation with said contact actuator and held in place by the spring pressed contact.
- 45 9. A lock switch including a contact carrier; a contact actuator; a lock having a floating oscillatable member in actuating relation with said contact actuator, and a shell enclosing the oscillatable lock member; and a spring between said contact carrier and the oscillatable lock member that positions the oscillatable lock member in its shell.
- 50 10. A lock switch including a contact carrier; a contact actuator; complemental contacts, inclusive of a spring pressed contact, coupled with said carrier and actuator at the adjacent faces thereof; and a lock having a floating oscillatable member in actuating relation with said contact actuator, and a shell enclosing the oscillatable lock member, the spring pressed contact serving to position the oscillatable lock member in its shell.

In witness whereof, I hereunto subscribe my name this 29th day of March A. D., 1923.

HARRY A. DOUGLAS.
